TUBE-BENDING MANDREL

Richard F. Attridge, Revere, and Ernest J.
Blouin, Salem, Mass.

Application May 3, 1945, Serial No. 591,768

2 Claims. (Cl. 153—63)

(Granted under the act of March 3, 1883, as
amended April 30, 1928; 370 O. G. 757)

1

Our invention relates to a tube-bending mandrel. It has to do more particularly, with a mandrel adapted to be disposed within a tube and having a flexibly mounted bearing unit located where the tube is to be bent in order to maintain the cross-sectional shape of the tube during bending.

In bending thin-wall metal tubes at present, especially with short-radius bends, it is customary to pack the tube with sand or fill it with molten resin which is allowed to solidify in order to prevent collapse of the tube at the bend. The tendency for the outer side of the tube to collapse is caused by the extreme tension developed in the material of the outer side during the bending operation. The sand or resin used in an attempt to prevent collapse of the tube is removed after bending the tube. Obviously, this method is slow and cumbersome.

A mandrel has been designed and used in an attempt to maintain the cross-sectional shape of the tube at the bend. This mandrel includes a rod having a ball swiveled on its end. The ball is adapted to be disposed within the tube where it is bent to prevent collapse thereof. We have found that the ball does not keep the tube from flattening on the outer side of the bend, especially when the tube is being bent to a short radius. This is due to the fact that the ball does not afford a bearing surface of sufficient extent lengthwise of the bend. Consequently, the flattening of the tube on the outer side of the bend usually occurs beyond the ball. Also, the ball is not mounted in a sufficiently flexible manner to permit it to swing properly with the tube as it is being bent.

One of the objects of our invention is to provide a tube-bending mandrel having means associated therewith for effectively maintaining the cross-sectional shape of the tube at the bend.

Another object of our invention is to provide a mandrel of the type indicated having a bearing unit of such a nature that it will afford sufficient bearing surface to prevent flattening of the tube on the outer side of the bend.

Another object of our invention is to provide a mandrel of the type indicated having the bearing unit mounted in a sufficiently flexible manner to permit it to swing properly with the tube as it is being bent.

According to our invention, we provide a tube-bending mandrel which includes a rod that has a bearing unit flexibly mounted on the end thereof. This bearing unit includes two balls, of the same diameter as the inside diameter of the tube, that are spaced apart by means of a sleeve disposed

therebetween. All of these parts are carried by a cable which is connected to the end of the rod.

The preferred embodiment of our invention is illustrated in the accompanying drawing wherein similar characters of reference designate corresponding parts and wherein:

Fig. 1 is a plan view, partly broken away, illustrating our tube-bending mandrel in position in a tube being bent.

Fig. 2 is a longitudinal sectional view illustrating in detail the bearing unit of our mandrel.

Fig. 3 is a transverse sectional view taken along the line 3—3 of Fig. 2.

Fig. 4 is a transverse sectional view taken along the line 4—4 of Fig. 2.

With reference to the drawing, we have illustrated in Fig. 1, clamping units 1 and 2 of a tube-bending machine. These units 1 and 2 are of the usual type, the unit 1 being mounted in a fixed

position and the unit 2 being mounted for swinging movement about a pivot point 3. This pivot point 3 is the center about which the tube 4 is to be bent. Initially, the clamping unit 2 is disposed directly adjacent to the unit 1, as indicated by

25 the dotted lines, so that these units are in side-by-side relationship. When the tube 4 is being bent, the unit 2 is swung about the pivot 3 and may, if desired, be swung through an angle of 180° to the full-line position indicated in Fig. 1.

30 The unit 1 and the unit 2 are provided with the usual tube-embracing dies which are opened and closed by handwheels 5 and 6, respectively.

A mandrel 7 is inserted in the tube 4 before it is bent. The mandrel is secured in a fixed position

35 within tube 4, prior to bending the tube, by suitable means (not shown) attached to the bending machine. The mandrel 7 includes a rod having its inner end 8 threaded for receiving the threaded end of a sleeve 9. This sleeve 9 is of

40 the same diameter as the internal diameter of the tube 4 to be bent. The sleeve 9 includes a bore 10 through which a flexible metal cable 11 passes. The cable is attached to the sleeve by means of a bushing 12 which fits into a complementary

45 socket 12a at the inner end of bore 10. The inner end of the cable 11 is secured to bushing 12 by the use of a wedge member 13 which expands the cable into a flared socket 14 in bushing 12, and by the use of solder indicated by numeral

50 15. The outer end of bore 10 is flared to form a chamber 16 which facilitates swinging of the cable 11 in all directions relative to the sleeve.

The cable 11 extends a considerable distance from the end of the sleeve 9. This extending portion of the cable carries the bearing unit 17 of

our invention. This bearing unit consists of balls 18 and 19, and a ball spacer 20, all of which are preferably formed of case-hardened steel.

Each of the balls 18 and 19 is of a diameter corresponding to the internal diameter of the tube 4 to be bent. Each of the balls has a bore 21, of cross-sectional area somewhat larger than that of the cable, extending therethrough and through which the cable 11 passes. Each of the bores 21 has flaring ends 22 to facilitate swinging of the cable 11 relative to the balls in all directions. The extreme outer end of the cable is secured in one of the flared sockets 22 of ball 19 by a wedge member 23 and solder, similar to the manner in which the opposite end of the cable is secured to the member 12. The spaced sleeve 20 has an internal diameter considerably larger than the cable 11 so that it will be loose thereon and has an external diameter considerably less than that of the balls. The ends of the spacer sleeve 20 are flared to provide a bearing socket in each end for the adjacent ball. The extreme edges of the sleeve 20 are machined to form curved seats 20a for the balls.

In bending the tube, the unit 2 is positioned in the dotted-line position indicated in Fig. 1 and the mandrel 7 is anchored in position on the machine. The mandrel will carry one of our bearing units 17 which will have balls of a diameter equal to the internal diameter of the tube to be bent and a sleeve 9 of corresponding diameter. The tube will be in the straight line position indicated by the dotted lines in Fig. 1. The mandrel will be so positioned that the outer end of sleeve 9 will lie in substantially the same plane as the center of pivot 3.

The machine is now operated to swing the unit 2 around the pivot 3. In the example shown, the unit 2 is swung through 180° but it is to be understood that it may be swung through any selected angle to bend the tube to any desired extent.

The bending of the tube may be considered as occurring in successive increments of length about a point at the center of the end of sleeve 9. Resistance to bending sets up tension on the outer side of the bend of the tube which tends to cause the tube to collapse or flatten. However, the outer side of the bend of the tube is supported against the spherical surfaces of balls 18 and 19 which are spaced sufficiently to hold the tube in its circular form. The bearing surface of the outermost ball 19 will be located a considerable distance from the end of sleeve 9. This is accomplished by employing two balls and the spacer 20 and by having cable 11 of a sufficient length to permit the inner ball 18 to move a considerable distance from the outer end of sleeve 9. As the tube bends, the bearing unit 17 will readily flex and move with it, due to the flexible cable 11 and also due to the fact that both the balls 18 and 19 will rock in the bearings in the ends of the sleeve 20. The surfaces of the balls engage the throat or inner side of the bend of the tube and will keep it in contact with the curved por-

tion 24 of the die unit 2. Such portion 24 will be of a radius of curvature corresponding to that to be produced on the throat or inner side of the bend. Thus, flattening of the outer side of the bend is prevented while the inner side is caused to effectively contact with the curved part 24 of the die.

After the tube is bent as indicated, the hand-wheels 5 and 6 are actuated to operate the dies 10 to release the tube. Then it is merely necessary to grasp the curved portion of the tube and pull the tube out of the dies and off the mandrel.

It will be apparent from the above description that we have provided a bearing unit on a tube-bending mandrel having a number of advantages. The bearing unit will provide sufficient bearing surface, properly located, to prevent flattening of the outer side of the bend of the tube. The bearing unit is mounted flexibly and is flexible in itself and, consequently, will properly position and adjust itself during the bending of the tube.

Various other advantages will be apparent.

The invention described herein may be manufactured and used by or for the Government of the United States of America for government purposes without the payment of any royalty thereon or therefor.

Having thus described our invention, what we claim is:

1. In a tube-bending mandrel, a sleeve of substantially the same diameter as the tube to be bent attached to the end of the mandrel, a flexible cable anchored within said sleeve and extending through a flared opening in the outer end thereof, a plurality of separate balls carried by the extending end of said cable and having a diameter corresponding to that of the internal diameter of the tube, a spacer sleeve carried by the cable between the balls and having flared 35 sockets in its ends in which said balls rock, the outer end of said cable being anchored to the outermost ball.

2. A tube bending mandrel comprising, a bearing unit adapted to be positioned within the tube 45 where it is to be bent, said bearing unit including a pair of separate ball members which correspond in diameter to the internal diameter of the tube, said ball members being spaced apart by a spacer sleeve, said spacer sleeve having bearing 50 sockets in each end and in which the adjacent ball members rock, and a flexible member carrying said ball members and said spacer sleeve.
